UNITED STATES PATENT OFFICE

141,321

DESIGN FOR A COMPOUND TOOL

William M. Gallagher, Oklahoma City, Okla.

Application February 6, 1945, Serial No. 117,787

Term of patent 14 years

(Cl. D54—13)

To all whom it may concern:

Be it known that I, William M. Gallagher, a citizen of the United States and a resident of Oklahoma City in the county of Oklahoma and State of Oklahoma, have invented the new, original, and ornamental Design for Compound Tools, of which the following is a specification.

Reference is had to the accompanying drawing forming part thereof, in which:

Fig. 1 is a top plan view of a compound tool, showing my new design;

Fig. 2 is a side view thereof;

Fig. 3 is a bottom plan view thereof.

I claim:

The ornamental design for a compound tool, as shown.

WILLIAM M. GALLAGHER.
